UNITED STATES PATENT OFFICE.

PABLO COGORNO, OF ROSARIO, ARGENTINA.

RECEPTACLE FOR LIQUIDS.

1,245,567.

Specification of Letters Patent.

Patented Nov. 6, 1917.

Application filed June 15, 1917. Serial No. 175,012.

To all whom it may concern:

Be it known that I, Dr. PABLO COGORNO, citizen of the Paraguayan Republic, residing at No. 870 Callao street, Rosario, Argentine Republic, have invented certain new and useful Improvements in Receptacles for Liquids, of which the following is a specification.

This invention relates to improvements in vessels or receptacles wherein liquids or the like are transported or preserved, and has for its object to provide a new type of vessel by which it is possible under all circumstances to verify the authenticity of the article therein contained and to prevent frauds.

In the accompanying drawings, which are given by way of example,

Figure 1 is a perspective view of the present invention as applied to a bottle.

Fig. 2 is a vertical section through the bottom part of said bottle.

As clearly shown in the drawings, the present invention consists in covering the vessel (in the form illustrated, a bottle *a*) with a mesh or netting of wire or any other convenient material *c*, which starts from the stopper *b* of the vessel, extends over its whole surface, and terminates at its free ends inside an upwardly-directed cavity *d* formed at the bottom of the vessel. This cavity is closed by a stopper or plug of any

convenient material *e*, which fits therein and in which the ends of the wires forming the netting are embedded, the plug itself being 35 fixed in position in the cavity by means of an adhesive paste or cement, so that the aforesaid free ends of the wires will be imprisoned and retained by the said plug.

It will be easily understood that in order 40 to empty the contents of the vessel, it will first be necessary to cut the mesh or netting, which fact may be observed at first sight, avoiding in this way all possibility of re-filling or fraud.

Although the invention has been shown as applied to a bottle, it must be clearly understood that it may be also applied to any other vessel, without departing from the scope of the present invention.

What I claim is:

A receptacle for liquids having a pouring opening at its top and an upwardly-directed cavity at its bottom; a stopper fitted in said pouring opening; a plug fitted in said cavity; a covering of netting extending across said stopper and entirely incasing the receptacle, the free ends of the strands of the netting extending into said cavity and being embedded in said plug; and means for securing said plug in said cavity.

In testimony whereof I affix my signature.

PABLO COGORNO.
